UNITED STATES PATENT OFFICE.

CHARLES F. BEAMAN, OF BROOKLYN, NEW YORK.

HAND-TRUCK.

SPECIFICATION forming part of Letters Patent No. 373,795, dated November 22, 1887.

Application filed February 3, 1887. Serial No. 226,466. (No model.)

To all whom it may concern:

Be it known that I, CHARLES F. BEAMAN, a citizen of the United States, residing in Brooklyn, Kings county, New York, (assignor to 5 JOSEPH ANNIN, of same place,) have invented an Improvement in Hand Trucks or Barrows; and I do hereby declare that the following is a full, clear, and exact description of the same, referring to the accompanying drawings, forming part of this specification.

My invention is in part an improvement on an invention for which an application for Letters Patent was filed by Joseph Annin, March 5, 1886, No. 194,186, and it has for its object 15 the increase of strength in the side pieces of hand trucks or barrows without increase of weight, or decrease of weight without decrease of strength, a more rigid and secure fastening for such side pieces to the body of the truck, 20 and the combination, with such side pieces, of more convenient handles.

Hitherto the side pieces of tubular barrows or hand-trucks have been made of round tubes or sections of round metal pipes fastened to 25 the body with clips tightened upon the tubular side pieces by bolts and nuts.

Tubes or pipes of circular cross-section, if of uniform thickness, are equally strong to resist strains in any direction. Consequently, 30 when used for the side pieces of hand trucks or barrows, they are no stronger to resist force applied in such manner as to tend to bend them in a vertical plane than they are to resist strains at right angles to such plane; but it is 35 well known that the strains of the first-mentioned kind are those to which they are constantly subjected, and that they are far more severe than those applied at right angles to the vertical plane. It is obvious, therefore, 40 that the correct principle upon which to construct these pieces, in order to secure lightness without sacrifice of strength, or to increase strength without undue weight, is to construct them in such manner that they are stronger 45 to resist vertical than horizontal strains. This is attained by flattening the tubes somewhat at the sides, thus imparting to the tubes an oval cross-section longer in vertical direction; and my present invention consists, partly, in 50 such construction of the side pieces of hand trucks or barrows. Moreover, as the clips, which embrace and clamp the side pieces of

oval cross-section, do not hold such side pieces wholly by friction, as is the case with side pieces of round tubing, they may be and are 55 made in my present improvement much lighter, and are closed together by lighter and smaller bolts and nuts than are necessary for round tubes; and my invention further consists in a construction in a hand truck or barrow 60 of tubular side pieces having an oval cross-section and a body provided with clips having correspondingly-shaped bearings for embracing and holding said side pieces, as hereinafter set forth; but the oval shape of the 65 section of the side pieces is not agreeable to the hand of the workman when such section is continued throughout the entire length of the same, handles and all, and its size necessary to give the requisite strength is greater than is 70 needed for the handles proper. I therefore not only reduce the ends of the side pieces to form handles of a convenient size, but also make these handles of circular cross-section, and these peculiarities of construction also form 75 features of my invention.

Referring now to the drawings, Figure 1 is a front or top view of a hand truck or barrow constructed in accordance with my improvement. Fig. 2 is a cross-section made on the 80 line *x x* in Fig. 1. Fig. 3 is a longitudinal section made on the line *w w* in Fig. 1. Figs. 4, 5, and 6 are respectively a longitudinal section of a portion of one of the side pieces and the handle of the same and cross-sections 85 made on the lines *y y* and *z z* in Fig. 3.

A represents the body of the truck, which is in this example of my invention made of cast-iron in a single piece, and which has formed upon it or thereunto attached clips *a*. 90 The cross pieces *b*, which join the sides of the body, are concaved in the usual manner for the safe support of casks or barrels. The sides of the body so joined are each made with a channel, *c*, on the under side, as best shown 95 in Fig. 2.

Each side piece, *B*, is passed through the clips *a* and channel *c* on one side of the truck, and its lower end is inserted into a socket, *d*, cast on the body of the lower part, as shown 100 in dotted outline in Figs. 1 and 3.

The handles are shown at *H*. They are of circular cross-section, and are represented as covered with some non-conducting material,

preferably of seamless tubes *h*, of toughened or parchmentized paper, as shown best in Fig. 4.

A cross-section of one of the side pieces is shown in Fig. 6. It will be seen that this section is oval in form, or that at top and bottom it is circular, and flat at the sides. It is easily made from ordinary round pipe or tubing flattened by dies or other methods well known in the art, and which need not therefore be here described. This oval side piece may be joined to the handle by a short portion of tube, which is not flattened, but is left of the original round cross-section, as shown in Fig. 5, and which is lettered *e* in Figs. 1, 3, and 4. The handle portion *H* is, however, preferably smaller than the part *e*, as well shown in Figs. 3 and 4, being so reduced by rolling, while the non-conducting tube *h* is slipped over the reduced portion, so as to be flush, or nearly so, with the part *e*.

The parts *B*, *e*, and *H* are made from a single piece of tubing or pipe, and are continuous one with another, as shown.

25 The channels *c* in the side pieces of the body are, in cross-section, the form of the upper half of the perimeter of the cross-section of the side pieces, *B*, as shown in Fig. 2, and from the lower margins of these channels extend downward the clips *a*, which embrace the side pieces and firmly retain them in said channels and in the aforementioned sockets *d*.

30 The clips are tightened upon the side pieces by bolts *f* and nuts *g*, two of the clips also serving as attachments for the angular supports *K*.

It will now be seen that the construction I have described attains the objects of the improvement above set forth in an extremely cheap and simple manner. It enables me to 40 produce a much lighter handier truck or barrow of a given strength than can be produced by the use of round pipes or tubes, and to use lighter clips and bolts than can be used for attaching circular side pieces to the body of the truck. At the same time a convenient handle, 45 not disagreeable on account of size or shape, is supplied.

Having thus described my improvement, what I claim as my invention, and desire to secure by Letters Patent, is as follows:

1. The combination, with the body of a hand truck or barrow having channels *c* and clips *a*, with oval contours, of side pieces, *B*, having in cross-section a similar contour fitted into said channels and clips and embraced by the 55 clips, substantially as and for the purposes set forth.

2. The combination, with the body of a hand truck or barrow, of tubular side pieces, *B*, of oval cross-section, having handles *H*, also tubular and of circular cross-section, formed in one piece with said side pieces, substantially as and for the purposes described.

3. The combination, with the body of a hand truck or barrow, of tubular side pieces, *B*, of oval cross-section, having handles *H*, also tubular, circular in cross section, smaller in diameter than the side pieces, and formed in one piece with said side pieces, substantially as and for the purposes specified.

4. In a hand truck or barrow, the combination, with the main part of the tubular side pieces, *B*, having oval cross-section, of tubular handles *H*, of smaller diameter than that of the side pieces and circular in cross-section, and 75 tubular joining parts *e*, also of circular cross-section, of a diameter larger than the handles, and connecting said oval parts with the handles, said oval parts, handles, and joining parts of each side piece being formed of one piece of 80 tubing or pipe, substantially as and for the purposes set forth.

5. In a hand truck or barrow, the tubular side bars, *B*, made of ordinary round pipe flattened into oval form along the main portion 85 attached to the body of the barrow, but left round at the handle extremities, substantially as shown and described.

CHARLES F. BEAMAN.
